US0D1101096S

(12) **United States Design Patent** (10) **Patent No.:** **US D1,101,096 S**
(45) **Date of Patent:** **** Nov. 4, 2025**

(54) **ULTRASONIC RODENT REPELLENT DEVICE**

(71) Applicant: **Yiyan Guo**, Ankang (CN)

(72) Inventor: **Yiyan Guo**, Ankang (CN)

(**) Term: **15 Years**

(21) Appl. No.: **29/917,985**

(22) **Filed:** **Nov. 23, 2023**

(51) **LOC (15) Cl.** **22-06**

(52) **U.S. Cl.**

USPC **D22/120**

(58) **Field of Classification Search**

USPC D22/120, 199; D30/199; D10/104.1, D10/106.1, 119.1; 119/174, 718, 719, 119/720, 721, 722, 723, 905, 908

Assistant Examiner — Jessie A Kwasney

(57) **CLAIM**

The ornamental design for an ultrasonic rodent repellent device, as shown and described.

DESCRIPTION

FIG. 1 is a front elevation view of an ultrasonic rodent repellent device showing my new design;

FIG. 2 is a back elevation view thereof;

FIG. 3 is a left-side view thereof;

FIG. 4 is a right-side view thereof;

FIG. 5 is a bottom plan view thereof;

FIG. 6 is a top plan view thereof;

FIG. 7 is a perspective view thereof;

FIG. 8 is another perspective view thereof; and,

FIG. 9 is another perspective view thereof.

1 Claim, 9 Drawing Sheets
